(57) **CLAIM**

The ornamental design for a label for a container, as shown and described.

DESCRIPTION

The patent or application file contains at least one drawing executed in color. Copies of this patent or patent application publication with color drawing(s) will be provided by the Patent and Trademark Office upon request and payment of the necessary fee.

FIG. 1 is a front view of a label for a container incorporating our new design, shown in gray scale with stippling representing a contrast of color;

FIG. 2 is a front view of an alternate embodiment of the design shown in gray scale with stippling representing a contrast of color;

FIG. 3 is a front view of an alternate embodiment of the design shown in gray scale with stippling representing a contrast of color;

FIG. 4 is a front view of an alternate embodiment of the design shown in color;

FIG. 5 is a front view of an alternate embodiment of the design shown in color;

FIG. 6 is a front view of an alternate embodiment of the design shown in color;

FIG. 7 is a front view of an alternate embodiment of a container label incorporating our new design, shown in gray scale with stippling representing a contrast of color;

FIG. 8 is a front view of an alternate embodiment of the design shown in gray scale with stippling representing a contrast of color;

FIG. 9 is a front view of an alternate embodiment of the design shown in gray scale with stippling representing a contrast of color;

FIG. 10 is a front view of an alternate embodiment of the design shown in color;

FIG. 11 is a front view of an alternate embodiment of the design shown in color;

FIG. 12 is a front view of an alternate embodiment of the design shown in color;

FIG. 13 is a perspective view of a container ornamented with an alternate embodiment of the design shown in gray scale;

FIG. 14 is a front view thereof;

FIG. 15 is a back view thereof;

FIG. 16 is a side view thereof;

FIG. 17 is a view of the opposite side thereof; and,

FIGS. 18 and 19 are top plan and bottom views thereof. The broken lines shown in the drawings depict environmental subject matter only and form no part of the claimed design.
